UNITED STATES PATENT OFFICE

2,535,269

HEAD SUPPORT FOR TELEPHONES

William Roy Coie, Des Moines, Iowa

Application September 13, 1946, Serial No. 696,693

1 Claim. (Cl. 179—156)

1

This invention relates to new and useful improvements and structural refinements in head supports for telephones, and the principal object of the invention is to provide a device of the character herein described, such as may be conveniently and effectively employed for supporting a French type, or a desk type telephone adjacent the mouth and ear of the user, so that the latter may have free hands for the performance of other tasks, such as the writing on memorandum pads, and the like.

A further object of the invention is to provide a head support which, by virtue of its function above described, is particularly suitable for use by persons possessing only one arm.

Another object of the invention is to provide a head support which may be easily and conveniently adjusted to suit the physical requirements of the user and in which the telephone may be readily applied or removed.

An additional object of the invention is to provide a head support which is simple in construction, pleasing in appearance, and which will not easily become damaged.

A still further object of the invention is to provide a head support which will readily lend itself to economical manufacture.

With the above more important objects in view, and such other objects as may become apparent as this specification proceeds, the invention consists essentially of the arrangement and construction of parts as illustrated in the accompanying drawings, in which:

Figure 1 is a perspective view showing the invention in use.

Figure 2 is a side elevation of the invention per se, taken in the direction of the arrow 2 in Figure 1.

Figure 3 is a front elevation of the subject shown in Figure 2, and

Figure 4 is a fragmentary cross sectional detail of a coupling bolt used in the invention.

Like characters of reference are used to designate like parts in the specification and throughout the several views.

Referring now to the accompanying drawings in detail, the invention consists of a head support designated generally by the reference character 10, the same embodying in its construction a pair of arcuate bands 11 and 12, which may be preferably formed from resilient material, such as spring steel.

The bands 11 and 12 constitute what may be referred to as a framework, the latter being adapted for positioning on the head, as is best

shown in Figure 1. It will be noted that the band 11, in effect, consists of a pair of complementary sections 13, these being longitudinally aligned and secured together in an overlapped relationship, as will be presently explained.

Each of the band sections 13 is formed adjacent the ends thereof with longitudinally extending slots 14, and a coupling bolt designated generally by the reference character 15 extends through the slots in the adjacent ends of the sections 13, whereby the sections are adjustably secured together.

The coupling bolt 15 consists of an internally threaded female member 16 and an externally threaded screw-like male member 17 which is receivable in the member 16, as is best shown in Figure 4. It will be noted that by simply loosening the bolts 15 and sliding the sections 13 with respect to one another, the overall length of the band 11 may be conveniently adjusted.

The aforementioned band 12 is formed adjacent the ends thereof with further, longitudinally extending slots 18, and additional couplings bolts 19, similar to the bolt 15, are employed for adjustably securing the bands 11 and 12 together.

An extension arm or link 20, provided with a longitudinally disposed slot 21, is attached adjacent one end thereof to one side of the framework, more specifically, to one of the sections 13, by means of an additional coupling bolt 22. The remaining end portion of the arm 20 is adjustably connected by another coupling bolt 23 to one limb of a substantially L-shaped bracket 24.

Said limb of the bracket 24 is slotted as at 25, and the remaining limb of the bracket projects laterally and carries a pair of complementary sections of a resilient clamp 26.

The sections of the clamp 26 are secured to the bracket 24 by a suitable screw or rivet 27 and the clamp is adapted to removably receive the handle portion 28 of the telephone 29.

Finally, it should be explained that a pair of pads 30, formed from resilient material such as soft rubber, or the like, are attached to the inner surfaces of the sections 13 adjacent the bolts 19 by means of suitable cord or wire 31, as will be clearly apparent from the accompanying drawings.

When the invention is placed in use, the framework is positioned on the head of the user, this being facilitated by loosening the bolts 15 and 19, whereupon the band sections 13 and the band 12 may be relatively adjusted to suit the physical requirements of the user. When the necessary

adjustments have been completed, the bolts 15 and 19 are simply retightened and further adjustments may then be undertaken with respect to the relatively positioning of the bracket 24 and the arm 20 to the framework.

It will be noted that sufficient adjustments are provided to facilitate the positioning of the clamp 26 in such location that when the telephone 28 is applied to the clamp, the ear-piece 32 and the mouth piece 33 will be held adjacent the ear and the mouth of the user respectively.

It will be also noted that the heads, so to speak, of the coupling bolt members 16, 17 are relatively flat, so that no discomfort is experienced by using the device. Furthermore, the provision of the pads 30 will considerably assist in assuring the comfort of the user.

The accompanying drawings illustrate the telephone 28 as being applied to the left hand side of the face. It should, of course, be understood that the telephone may be applied to the right hand side with equal effectiveness, this being accomplished by simply attaching the arm 20 to the relatively opposite of the sections 13.

While in the foregoing there has been shown and described the preferred embodiment of this invention it is to be understood that minor changes in the details of construction, combination and arrangement of parts may be resorted to without departing from the spirit and scope of the invention as claimed.

What I claim as my invention is:

In a head support for telephones, the combin-

ation of a frame adapted for positioning on the head of a user, a downwardly extending link provided with a longitudinal slot, a clamping bolt positioned in the upper portion of said slot and adjustably attaching said link to said frame, an L-shaped bracket affording a downwardly extending long arm and a laterally projecting short arm, said long arm being provided with a longitudinally extending slot, a second clamping bolt positioned in said last-mentioned slot and extending through the lower portion of the first slot to adjustably connect said bracket to said link, and a pair of coacting clamp sections secured to opposite surfaces of said short arm and adapted to receive a telephone therebetween.

WILLIAM ROY COIE.
